UNITED STATES PATENT OFFICE.

JOHN CORYELL, OF DETROIT, MICHIGAN.

MULTIPLE-SCREW JACK.

1,396,259.

Specification of Letters Patent.

Patented Nov. 8, 1921.

Application, filed August 13, 1920. Serial No. 403,237.

To all whom it may concern:

Be it known that I, JOHN CORYELL, a citizen of the United States, residing at Detroit, in the county of Wayne and State of Michigan, have invented a certain new and useful Improvement in Multiple-Screw Jacks, of which the following is a specification.

This invention relates to multiple screw jacks of the type in which one screw rotates 10 or telescopes inside the other. The object of the invention is to operate such a jack by continuous rotary movement and to do it in such a manner that the jack operates comparatively rapidly but with great power 15 and over a comparatively great distance or height whereby the device is especially applicable for heavy work such as in connection with heavy trucks, and in other places as in factories where heavy loads are to be lifted. 20 The invention consists in a novel combination of parts obtaining the foregoing and other objects which can be easily and comparatively cheaply made, which is satisfactory in use and is not readily liable to get 25 out of order. More particularly the invention consists in many features and details of construction hereafter more fully set forth in the specification and claims.

Referring to the drawings in which similar numerals represent the same parts throughout the several views,

Figure 1 is a vertical sectional detail view of mechanism illustrating this invention in its preferred form.

Fig. 2 is a detail plan view on the line 2-2 of Fig. 1.

Fig. 3 is a reduced scale detail plan view on the line 3-3 of Fig. 1.

The jack is supported upon a suitable base 40 having a foot 12 of ordinary construction adapted to rest upon the floor. The side 10 of this base 10 is preferably provided with a convenient handle 14 by which the entire mechanism may be conveniently transported 45 by the operator who takes hold of the handle. Telescopically mounted on the base 10 and guided for vertical movement only thereon by the handle 14 and the guide screw 16 entering suitable slots 17 and 19 respectively 50 is a hollow case 18 preferably made of two parts, the upper one 18^a being a cover readily detachably securable in normal position by one or more securing devices, such as set screws 20.

55 The base 10 is vertically bored to receive the external or lower screw 22 whose outer

circumference is provided with screw threads 24 intermeshing with other threads 26 formed on the interior of the base 10. The upper end of the screw 22 carries a worm 60 wheel 28 driven by a worm 30 carried by a shaft 32 rotatable by application of a wrench or other tool to its non-circular end 34 readily accessible to the operator.

The upper cover member 18^a is perforated 65 in alignment with the axis of the screw 22 and the opening is closed by a bearing plate 36 detachable secured in place by any suitable means as for instance the bolts or screws 38. This bearing plate 36 is in turn provided with an opening 40 of sufficient size 70 so that internal or upper screw 42 can freely pass down through it as shown in Fig. 3. This screw 42 which also telescopes in screw 22 is provided along its length with a keyway 44 slidably entered by a key 46 mounted in the perforation 40 of plate 36. This will be referred to as a spline connection. This screw 42 is provided with screw threads 48, 75 of opposite pitch from the screw threads 80 24 on the outside of the outer screw 22, engaging internal screw threads 50 cut on the inside of screw 22.

The result of the foregoing construction is that when the operator rotates shaft 32 85 he causes the worm 28 to rotate the outer screw 22 in one direction and that as the upper screw 42 is, through threads 48-50, threaded into it in the opposite direction, and that as screw 42 is held against rotation by the key 46, screw 42 travels longitudinally with reference to the outer screw 22 as well as along with it in the same direction. The ultimate result is that the speed of lifting or lowering, as the case may be, 95 is, assuming the pitches of both sets of screw threads are the same, double of what it would be were only one screw used and the height of lift or lower is correspondingly increased.

The upper end of screw 42 carries the load 100 engaging block 52. As the screw 42 does not rotate this block is preferably pinned to it. As soon as the load lifting head 52 engages the load which has to be lifted, it through the agency of pin 54, holds the screw 105 42 against rotation and thus relieves the strain which would otherwise exist at the key 46.

The base and case are each non-rotatable and will be referred to as non-rotatable 110 members.

Having thus described my invention what

I claim as new and desire to secure by Letters Patent, is:—

1. In mechanism of the class described, the combination of two separated non-rotatable members one of which is a base, a pair of screws telescoping with each other and with the non-rotatable members, screw threads between said screws, other screw threads between one screw and one non-rotatable member, a spline connection between the other screw and the other non-rotatable member, and means for rotating the rotatable screw.
2. In mechanism of the class described the combination of two separated non-rotatable members, one of which is a base, a pair of screws telescoping with each other and with the non-rotatable members, screw threads between said screws, other reversely pitched screw threads between one screw and one non-rotatable member, a spline connection between the other screw and the other non-rotatable member, and means for rotating the rotatable screw.
3. In mechanism of the class described, the combination of two separated non-rotatable members one of which is a base, means permitting reciprocation of one of said members with reference to the other, a pair of screws telescoping with each other and with the non-rotatable members, screw threads between said screws, other screw threads between one screw and one non-rotatable member, a spline connection between the other screw and the other non-rotatable member, and means inclosed within one of said non-rotatable members for rotating the rotatable screw.
4. In mechanism of the class described, the combination of two separated non-rotatable members one of which is a base, means permitting reciprocation of one of said members with reference to the other, a pair of screws telescoping with each other and with the non-rotatable members, screw threads between said screws, other reversely pitched screw threads between one screw and one non-rotatable member, a spline connection between the other screw and the other non-rotatable member, and means inclosed within one of said non-rotatable members for rotating the rotatable screw.
5. In mechanism of the class described, the combination of a base, one screw threaded into the base, a second screw inside the first into the base, a second screw inside the first screw threaded therein, the screw threads between the base and the first screw being in one direction and the other set of screw threads being in the opposite direction, means holding the second screw against rotation while permitting it to reciprocate to and from the base, and means for rotating the first screw, for the purposes set forth.
6. In mechanism of the class described, the combination of a base, one screw threaded into the base, a second screw inside the first screw threaded therein, the screw threads between the base and the first screw being in one direction and the other set of screw threads being in the opposite direction, a case member for the screws mounted for reciprocation with reference to the base, and means for preventing rotation of the case member during such reciprocation, operating means for the first screw inside said case, and means on said case holding the second screw against rotation while permitting it to reciprocate through the case to and from the base, for the purposes set forth.
7. In mechanism of the class described, the combination of a base, one screw threaded into the base, a second screw inside the first screw threaded therein, the screw threads between the base and the first screw being in one direction and the other set of screw threads being in the opposite direction, a case member for the screws mounted for reciprocation with reference to the base, and means for preventing rotation of the case member during such reciprocation, worm gear operating means for the first screw inside said case operable from outside the case, and means on said case holding the second screw against rotation while permitting it to reciprocate through the case to and from the base, for the purposes set forth.
8. In mechanism of the class described, a base member suitable for standing upon a support, a screw threaded into a vertical opening in the base for movement with reference thereto, a second screw inside the first and engaging the same in screw threads of opposite pitch from the threads between the first screw and base, a worm gear mechanism at the upper end of the first screw for operating it, a supporting case for said worm gear mechanism traveling with the gear mechanism and the first mentioned screw to and from the base, pin and slot connections between the case and the base permitting its reciprocation with reference to the base, preventing its rotation with reference to the base, a spline connection between the reciprocating case and the second screw permitting reciprocation of the second screw, with reference to the case and base, for preventing its rotation with reference thereto, and a load carrying cap rigidly attached to the upper end of the second screw, for the purposes set forth.
9. In witness whereof, I have hereunto subscribed my name in the presence of two witnesses.

JOHN CORYELL.
